SWING

David Saint, Elverson, Pa., assignor to Graco Metal Products, Inc., Elverson, Pa.

Filed Oct. 18, 1971, Ser. No. 190,427

Term of patent 14 years

Int. Cl. D6—01

U.S. Cl. D6—10

FIG. 1 is a front elevational view of a swing showing my new design;

FIG. 2 is a right side elevational view of the swing of FIG. 1;

FIG. 3 is a rear elevational view of the swing of FIG. 1;

FIG. 4 is a left side elevational view of the swing of FIG. 1;

FIG. 5 is a top plan view of the swing of FIG. 1.

I claim:

The ornamental design for a swing, as shown.
